Albert H. Neller

UNITED STATES PATENT OFFICE

ALBERT H. NELLER, OF FAIRFIELD, IOWA

WATER BOWL

Application filed December 12, 1929. Serial No. 413,515.

My invention relates to water bowls to be used by animals, and to be operated by them to get water when they want it, and it consists principally of an improvement in the 5 means for holding the bowl in operative position, which will be fully explained hereafter. Also, of other improvements in the construction of the bowl and its attachments, which will also be fully explained in this 10 specification.

In the accompanying drawings forming a part of this specification, Fig. 1 is a perspective of a water bowl and its attachments, embodying my invention. Fig. 2 is a longitudinally disposed vertical section of the bowl and most of its attachments on line 2-2 of Fig. 1, a side view being shown of some parts of the attachments as will be hereafter explained. Fig. 3 is a vertically 20 disposed transverse section on line 3-3 of Fig. 2, looking in the direction of the arrow.

Fig. 4 is a horizontal section on line 4-4 of Fig. 2 looking downward in the direction 25 of the arrow, a considerable portion of the outstanding edge of the bowl being broken away. Fig. 5 is a top view of the attachable edge of the bowl, all the attachments being removed and the other edges of the bowl 30 being cut away. Figs. 6, 7 and 8 are detail views which will be hereafter described. In Figs. 3 and 4 the cut away portions of Fig. 2 through which the lines 3 and 4 pass are replaced to make them complete in these 35 figures.

Referring to the drawings, the reference letter A represents the water bowl and B a stall post to which the bowl is attached by 40 means of a casting C. The cross section end of the casting C adjoining the post B is centrally curved or indented, to more readily fit the post and is provided with laterally extended lugs D which are slotted to receive 45 the ends of a U bolt E, by means of which the casting is securely connected to the stall post. The central part of the casting C is 50 made more or less rectangular and is preferably hollow, as shown in Fig. 3. It is fitted with a bolt F passed up vertically

through this part of the casting for the purpose of connecting the bowl thereto.

The edge of the bowl to be connected to the casting C is provided with an outwardly extended horizontally disposed portion G, 55 as most plainly shown in Fig. 5. The part G has an opening H which may be passed up over the head of the bolt F by placing the part G close to the stall post, and then, by drawing the bowl out from the post, the 60 neck of the bolt will be drawn into the slot in the opening H, and by tightening the nut I on the upper end of the bolt F, which is preferably in the form of a cap nut, the 65 head of the bolt will be drawn up against the under side of the central portion of the part G adjoining the slot in the opening H, and the bowl will be held securely against the under side of the central horizontally 70 extended portion of the casting C.

The other end, or what may be called the inner end of the casting C it being over an inner portion of the bowl, is provided with a tubular portion J which is preferably set vertically downward and at substantially 75 right angles to the main body of the casting. The upper end, and preferably the enlarged part of this tubular portion J is interiorly threaded and is adapted to be connected to the threaded end of a vertically disposed wa- 80 ter conducting pipe K, to conduct water into said tubular portion J. By connecting the pipe K to this end of the casting C, and in line with its downwardly extended portion J, all the central portion of the casting C will 85 be left free for the connection to its lower side of the upper side of the horizontally ex- 90 tended portion G of the water bowl. A valve L having a downwardly projecting stem R (see Fig. 8) encircled by a spring, is inserted 95 in this tubular portion of the casting C as shown in Fig. 2. An operating member M generally called the "nose piece", is pivoted to the lower end of the tubular portion J to operate the valve as follows.

The extreme lower end of the part J is pro- 95 vided with a lateral portion N extended in- 100 wardly towards the center of the bowl. This lower end is made open in its center and is fitted on each side with inwardly disposed

lateral lugs O, as most plainly shown in Figs. 1 and 6. The member M is provided with a projecting portion P, the end of which is fitted to enter the opening between the lugs O, and it is also fitted with laterally disposed outstanding pivot pins Q, which are adapted to rest in the recesses of the lugs O. Before the bowl is connected to the casting C said end of the member M is passed below the lugs O until the pins Q have passed beyond the edges of the recesses, and then, being raised slightly and drawn backward, the pins Q will enter the openings of said recesses in the lugs O, one on each side, and will rest in the recesses and will be pivoted therein.

As shown by Fig. 8, the downwardly extended pin R of the valve is provided with a casting S screwed thereon. The lower end U of the casting S is narrowed to come between the upwardly extended sides on the end P of the nose piece M and to rest on a central connecting part T between the lower portions of said sides. When in this position, the part T will be in contact with the lower end U of the casting S, and when properly adjusted, which can be done by screwing the casting S up or down on the lower end of the pin R, the other end of the nose piece M will be held up a distance from the bottom of the bowl by the pressure of the spring on the pin R against the casting S, the upper end of the spring being held against the under end of the valve seat, or against an inner portion of the tubular part J just below the valve L as shown in Fig. 2.

When in this position a pressure of the animal's nose against the outstanding portion of the nose piece M, as the animal will do when wanting a drink, will press it downward and will raise the other end T against the lower end U of the casting S, which will raise the valve L to open position, and will admit water into the bowl. When the pressure of the animal's nose is removed, the tension of the spring will press the casting downward and will raise the outstanding portion of the nose piece to its former position. This will close the valve and shut off the flow of the water when the nose piece will again be in the position to be operated by the animal.

In Fig. 2 the stall post B, the end of the casting C attached thereto, the cap nut I, the upper part of the tubular portion J, the water pipe K, and the valve L with its spring and stem R (Fig. 8) and its casting having the lower end U, are all shown in side view or perspective. The balance of the figure is a longitudinally disposed vertical section. It is preferable that the upper edges of the bowl extension G and the lower edges of the casting C be beveled to fit each other as shown in Fig. 3; for by this means the bowl will be held rigidly in its operative position when the bolt F is tightened, and it cannot be shifted

out of this position by the nosing of the animal.

The principal improvement of my invention is in the improved manner of connecting the bowl to the lower side of the extended horizontal portion of the casting C. The casting as shown in the drawing, has only one downwardly disposed part which is inside of the bowl, and it has an extended horizontal part between that and the stall post B, to the lower side of which the extended portion G of the bowl rigidly and very securely fastened by the vertically disposed bolt F. While it is preferable to have this downward extension of the casting on the inside of the bowl, other means of conducting the water into the bowl may be used.

The construction of this bowl and its connections are extremely simple and the cost of manufacture is reduced to the minimum. The valve mechanism may be readily adjusted to admit a larger or a smaller amount of water into the bowl. It is an advantage to have the nose piece pivoted in a lower portion of the bowl and also to have the water thus admitted into the bowl. The bowl is readily attached to or detached from its connections, and there are no rough projecting portions anywhere to come in contact with the animal's nose. In all respects it is of the simplest and most advantageous construction.

Having thus described my invention, what I claim is—

1. In water bowls adapted to be attached to an animal stall or pen to furnish water for the animal therein, a horizontally disposed elongated casting adapted to have one of its ends connected to and supported by a portion of said stall or pen, and the other end of the casting deflected downward to conduct water into the bowl, a water bowl having a horizontally disposed extension applied to the lower side of the horizontal portion of the casting and rigidly connected thereto, a vertically disposed water conducting pipe being connected to the end of the casting having said downward deflection, and in substantially alignment therewith, and appropriate means to admit water into the bowl.

2. In water bowls adapted to be attached to an animal stall or pen to furnish water for the animal therein, a horizontally disposed elongated casting adapted to have one of its ends connected to and supported by a portion of said stall or pen, and the other end adapted to conduct water into the bowl, a water bowl having on its upper edge a horizontally disposed extension applied to the lower side of the casting and rigidly connected thereto, the elongated lower side of the connecting casting being adapted to fit the upper side of the horizontal extension of the bowl, and appropriate means to admit water into the bowl.

3. In water bowls adapted to be attached

to an animal stall or pen to furnish water for the animal therein, a horizontally disposed elongated casting adapted to have one of its ends connected to and supported by a portion of said stall or pen, and the other end adapted to conduct water into the bowl, a water bowl having a horizontally disposed extension applied to the lower side of the casting and connected thereto by a vertically disposed bolt passed through the adjoining parts, and appropriate means to admit water into the bowl.

4. In a water bowl having an extended portion adapted to be applied to the under side of a horizontally disposed casting, and to be held rigidly in contact therewith by a vertically disposed bolt passed through a central part of said extended portion, and also, through the casting, the upper edges of said extended portion, and the contacting lower edges of the casting being beveled to fit each other, and to thus more securely hold the bowl in operative position.

5. In a device of the character described, a horizontally disposed casting having one end fitted for connection with a portion of an animal stall or pen, and the other end formed with a vertically disposed tubular portion extending downwardly below the horizontal portion of the casting, and containing a water valve with a downwardly extended spring encircled stem, the lower end of said tubular portion being open and provided with inwardly extended lugs, a water bowl having an outward horizontally extended portion attached to the under side of the central part of aforesaid casting, a nose piece having an extended end provided with transversely extended pivot pins adapted to enter the opening in the lower end of the tubular portion and to be pivoted on said inwardly extended lugs, and to come in contact with the lower end of the spring controlled valve extension therein, whereby an animal by pressing downward on the outer portion of the nose piece will open the valve and admit water to the bowl.

6. In water bowls adapted to be attached to an animal stall or pen, and provided with a valve to be operated by an animal to admit water into the bowl, a horizontally disposed casting adapted to hold the bowl in operative position, said casting having one end formed for connection with a portion of the stall or pen, the other end being formed with a tubular portion containing the valve, a water bowl having an outward horizontally disposed portion provided with an opening therein with an extended slot on an outer side of the opening, a bolt having a head on its lower end and a nut on its upper end passed up through a suitable opening in the central part of the aforesaid casting, whereby the bowl may be attached to said casting by passing the opening in the extended por-

tion of the bowl up over the head of the bolt, and then sliding the bowl so as to bring the slot in the opening by the neck of the bolt, the bowl being fastened in position by turning down the nut on the upper end of the bolt and means in the bowl whereby an animal may open the valve to admit water into the bowl.
